UNITED STATES PATENT OFFICE

ROBERT W. CANFIELD, OF WEST HARTFORD, CONNECTICUT, ASSIGNOR TO HARTFORD-EMPIRE COMPANY, OF HARTFORD, CONNECTICUT, A CORPORATION OF DELAWARE

SUCTION DEVICE FOR GATHERING MOLTEN GLASS

Application filed October 11, 1928. Serial No. 311,757.

This invention relates to such gathering devices employed in the manufacture of glassware, to separate a mass of glass of suitable size for making a single article, from 5 a pool of molten glass. This gathering device may be either a cup for separating a suitable amount of glass which is later delivered to a mold, or the suction gathering device itself may constitute a mold such, for 10 example, as is commonly employed in the well-known Owens bottle machine.

A desirable material for the glass contacting portion of such a gathering device is carbon, or a carbon composition, preferably a 15 graphite composition, this being described in an application Serial No. 203,391, filed by Karl E. Peiler, on July 5, 1927. In the use of carbonaceous material for this purpose (hereinafter referred to as the cup, irrespec- 20 tive of whether it is simply a gathering device or a preliminary shaping mold) care must be exercised to prevent chipping or defacing the cup material by contact with co- 25 operating metal parts.

The object of the present invention is to 30 provide a suction gathering device of the character described, having the greater part of its glass contacting surface formed of carbonaceous material and in which such parts of this cup as cooperate or contact with metallic moving parts, are provided with metallic contact portions. Such essential moving parts in a device of this kind, are a valve 35 for closing the connection between the cavity of the cup and a source of suction, and, in some instances, a severing device which cuts the string of glass connecting that in the cup with that in the pool.

The object of this invention is accomplished 40 by providing a suction cup or the like, of non- metallic material, having a valve controlling the application of suction to the cavity of the cup, with a metallic bushing forming that portion of the mold cavity which is engaged 45 when the valve seats. When the glass in the cup cavity is severed by a blade which cooperates with the lower edge of the cavity, a metallic ring is provided to form the wall of the cup cavity which contacts with the blade. 50 One embodiment of the invention for carry-

ing out these objects and such others as may hereinafter appear is shown in the accompanying drawing, in which:—

Fig. 1 is a vertical section through a suction gathering cup, the arm by which it is carried and a portion of the vessel containing a pool of molten glass;

Fig. 2 is a plan view of the bushing surrounding the valve;

Fig. 3 is a section through the valve stem; and

Fig. 4 is a partial sectional view corresponding to Fig. 1, showing the cup as used with a sliding shear blade to sever protruding glass.

The gathering cup 5 is secured in an arm 6 by a clamping screw 7 and a partial vacuum is communicated to the cavity therein through an opening in the upper end. As illustrated, this cup would be used for delivering a gather of glass to a mold or other shaping device, but this invention comprehends the use of a cup which may be in itself a shaping mold, such as the blank or parison molds used in the well-known Owens' machines. The lower open end of the cup is moved into contact with the surface of a pool of molten glass in a container 9 which may be stationary or rotary and the glass is drawn up into the cavity until the upper advancing end of the glass engages a valve 10 which is lifted thereby to close the opening. In order to prevent damaging the cavity wall by the valve, the opening is formed in a bushing 11 and the seat of the valve 10 is formed in the lower end of the bushing, thereby preventing the valve from engaging directly against the material from which the body of the suction cup is formed. Bushing 11 has a flange 11a formed thereon which serves to reinforce the cup 11 and to provide an air-tight joint between the cup and the member 6, as will be obvious from Fig. 1. The flange 11a overlies the vertical opening in the member 6, and when the cup 5 is mounted in the said member, the engagement of the flange 11a with the top of the recess serves to hold the bushing in position in said cup.

The valve stem 21 is provided with wings as shown in Fig. 3 and the upper end of the stem carries lock nuts 12 which may be ad-

justed to limit the downward movement of the valve. The upper end of the bushing is provided with projections 13 to prevent the lock nuts from closing the opening when the valve is in its lower position. As illustrated, the valve is moved to open or lowered position by gravity, but if desired a light spring may be provided to hold the valve normally in open position.

10 After the cavity has been filled with molten glass, as has been described, the arm 6 is lifted from the surface of the pool by any suitable mechanism (not shown), and moved into position to deliver the gather to a mold or other 15 shaping instrumentality. The string of glass connecting the gather and the surface of the pool may be severed after the cup has been lifted slightly by suitable severing devices which in themselves form no part of the present invention. One such device is shown in 20 an application filed by Karl E. Peiler on December 7, 1926, Serial No. 153,093, now Patent No. 1,692,858, dated November 27, 1928, which shows a pair of shears spaced from the bottom of the cup and therefore not contacting therewith.

Another form of severing device is that used in Owens machines, in which a blade cuts off the glass by cooperation with the bottom of the cup. When this form is used, the present invention contemplates the provision of a metal ring with which the severing blade contacts so as to prevent wear or damage to the lower end of the nonmetallic cup.

35 As shown in Fig. 4, the cup 5 is provided at its lower end with a ring 15 against which a blade 16 slides to produce a shearing action therebetween. The ring 15 may be permanently attached to the bottom of the cup, or 40 if the opening of the ring is smaller than that of the cup, the ring may be removed to permit the delivery of the charge from the cup. Thus the ring 15 provides a metallic marginal edge for the cup cavity, with which 45 the blade 16 coacts to sever the glass.

It is to be understood that the described embodiment of the invention is selected for the purpose of illustration only, and that various modifications may be made within 50 the scope of the appended claims.

What I claim is:

1. A suction gathering device comprising a dipping member having a recess formed therein, a cylindrical cup of graphite composition mounted in said recess, the entrance end of said cup being adapted to move into contact with the surface of the pool of glass, a vacuum passage in said member, a bushing mounted in said cup, said bushing being rigidly secured in position and providing communication between the interior of said cup and said vacuum passage, whereby vacuum may be applied to said cup to fill the cup with glass, a cut-off valve mounted in 45 said bushing and prevented from injuring

said cup by said bushing, a shear blade for severing a tail of glass depending from said cup, and a device movable into engagement with the entrance end of the cup cavity for preventing injury to said cup by said shear blade.

2. A suction gathering device for preshaping mold charges, comprising a rigid suction head having a recess formed therein, a one-piece cup of carbonaceous material secured to said recess, said cup being longer than said recess, and having a cavity formed therein for the shaping of mold charges and the delivery of the shaped charges through its bottom end, a flanged bushing rigidly mounted in the upper end of said cup, the flange on said bushing being arranged for engagement by a part of the suction head, whereby the mounting of the cup in the head serves to hold the bushing in position, and a vacuum cut-off valve in said bushing, said bushing serving to protect the cup from injury by said valve.

3. A suction gathering device for preshaping mold charges, comprising a rigid suction head having a cylindrical recess formed therein, a one-piece cylindrical cup of carbonaceous material mounted in said recess, said cup projecting below said recess, means for removably securing said cup in said recess, said cup having a cavity formed therein for the shaping of mold charges and the delivery of the shaped charges through its bottom end, a flanged bushing rigidly mounted in the upper end of said cup, the flange on said bushing being arranged for engagement by part of said head, whereby the mounting of the cup in the recess of the head serves to hold the bushing in position, a vacuum cut-off valve in said bushing, a vacuum passageway in said head leading to said valve, said valve being arranged to be closed by the glass which is gathered in the cup, and said bushing serving to protect the cup against injury by the valve and to provide a seat for the valve.

4. Suction gathering apparatus comprising a suction head, a cup of carbonaceous material secured in said head, said cup having a cavity formed therein for the shaping of mold charges and for the discharge of such charges from the cup, the bottom portion of said cup projecting below the suction head structure, glass severing means, and a metallic member adapted to be moved into contact with the bottom of said cup to protect the cup from abrasion by said severing means, and said member being shaped to provide a bearing surface on its under side for said severing means.

Signed at Lancaster, Ohio, this 8th day of October, 1928.

ROBERT W. CANFIELD.
